UNITED STATES PATENT OFFICE.

ERNEST A. HUSSAR, OF SOMERVILLE, MASSACHUSETTS.

CLOSURE FOR CONTAINERS.

Application filed November 3, 1923. Serial No. 672,653.

To all whom it may concern:

Be it known that I, ERNEST A. HUSSAR, a citizen of the United States, residing at Somerville, in the county of Middlesex and 5 State of Massachusetts, have invented new and useful Improvements in Closures for Containers, of which the following is a specification.

This invention may be embodied in a closure 10 suitable for use with a container comprising a body portion charged with semi-fluid material to be dispensed, and a neck through which the material is forced outward by pressure exerted upon it. The material may be tooth or shaving paste, adhesive paste, grease used for lubrication, or any other material adapted to be extruded through a relatively small bore in the neck. The body may be a collapsible tube, adapted 15 to be compressed to cause the extrusion of the material, or it may be non-collapsible and provided with means such as the piston employed in a grease gun to cause the extrusion.

20 The invention may also be embodied in a closure suitable for use with a grease or oil cup, or other like container, having a neck through which material is inserted from the exterior and passes inward through the neck.

25 The object of the invention is to provide improved means for opening and closing the neck, having the advantages hereinafter stated.

30 Of the accompanying drawings forming a part of this specification—

35 Figure 1 is a perspective view of the neck and a portion of the body of a container, the neck embodying certain features of the invention.

40 Figures 2 and 3 are perspective views, respectively, of the valve member and the cap hereinafter described.

45 Figure 4 shows the neck, the valve member, and the cap assembled, the neck and valve member being shown in elevation, and the cap in section, the valve being in its open position.

50 Figure 5 is a view similar to Figure 4, showing the valve in its closed position.

55 Figure 6 is a section on line 6—6 of Figure 4.

Figure 7 is a sectional view, showing the cap before its engagement with the neck.

Figure 8 is a section on line 8—8 of Figure 7. 55

Figure 9 is a view similar to Figure 4, showing a modification.

Figures 10 to 17, inclusive, show a different embodiment of the invention.

The same reference characters indicate the 60 same parts in all the figures.

Referring first, to Figures 1 to 8, inclusive, 12 designates the body, and 13 the tubular neck of a container. The neck is cylindrical and its bore 14 is surrounded by an annular 65 concave seat 15. In the bore of the neck is a peripheral groove 16, and in one side of its outer end is a recess 17.

18 designates an internally cylindrical cap fitting the neck and provided with a crimped 70 flange 19 at its lower end, occupying the groove 16, the cap being thus adapted to turn without endwise movement on the neck, confined against removal from the neck and held with its outer end or head portion 75 spaced from the outer end of the neck. The head portion of the cap is provided with a centrally located outlet orifice 20, and with a concave internal seat 21, surrounding the orifice. 80

22 designates a substantially spherical valve member interposed movably between the seat 21 and the outer end of the neck. The outer portion of the valve member has a convex upper face bearing on and closely 85 fitting the seat 21. The lower portion of the valve member has a convex lower face, bearing on and closely fitting the seat 15 on the neck. The valve member is provided with a port 23, opening on said convex faces, and 90 with two oppositely projecting trunnions 24, which are adapted to turn in trunnion bearings 25, formed in the cap at opposite sides of the outlet orifice 20, as shown by Figures 7 and 8. The trunnions are interposed between 95 said bearings and the outer end of the neck, and are adapted to turn in contact with the bearings and neck.

One of the trunnions 20 is provided with an ear 26, formed to enter and move in the 100 neck recess 17.

The arrangement is such that the cap 18 and the neck 14 may be located in the different relative positions shown by Figures 4 and 5, either by turning the cap on the neck, 105 or by turning the neck in the cap. When

the parts are in the relative positions shown by Figure 4, the valve bore 23 is in alignment with the neck bore 14 and with the cap outlet 20, as shown also by Figure 6. When 5 the parts are in the relative positions shown by Figure 5, the valve port 23 is out of alignment with the bore 14 and outlet 20, and is closed by the seat 21.

The ear 26 and recess 17 constitute an embodiment of coupling means for imparting 10 a partial rotation to the valve member when the cap is turned, the valve member turning on an axis formed by the trunnions. The engagement of the trunnions with the bearings 15 25, causes also a turning movement of the valve member with the cap on an axis between and at right angles with the trunnions, although this last-mentioned turning movement is not caused in the embodiment 20 of the invention shown by Figure 9 and hereinafter described.

It will now be seen that a turning movement of the cap in either direction causes 25 the valve member to turn, the result being the opening of the port 23 when the cap is turned in one direction, and the closing of 30 said port when the cap is turned in the opposite direction. When the valve member is closed, its convex upper and lower portions closely fit the concave seats 21 and 15, so that 35 the container is effectively sealed.

The outer side of the head portion of the cap, and the outer portion of the valve member are so formed that they are substantially 35 flush with each other when the valve member is closed, as shown by Figure 5, so that the exposed surfaces may be conveniently 40 wiped and sterilized.

Figure 9 shows a modification of the 45 coupling means for imparting a partial rotation to the valve member. In this modification the valve member is provided with an upwardly projecting ear 26^a, engaging a recess 17^a in a projection 28 on the head portion of the cap 18, the valve member turning only on an axis formed by its trunnions.

It is obvious that the neck may communicate with a receptacle such as a grease or oil 50 cup, to be charged with material which passes inward through the neck when the valve member is opened, and is supplied by means such as a grease gun or oil can applied to the orifice 20 which, in this case, is 55 an inlet or receiving orifice instead of an outlet.

The valve member may be opened and closed by a partial rotation only, on an axis at right angles with the axis of the cap, as in 60 the embodiment of the invention shown by Figures 10 to 17. In this embodiment the valve member, designated by 30, is of concavo-convex form, its upper side constituting a convex face fitting the concave seat 21, which surrounds the orifice 20 in the cap head. The lower edge of the valve member

is provided with projections 31, which are, in effect, trunnions, performing the function of the trunnions 24, and adapted to turn in bearings 32, formed by grooves in the outer end of the neck 13. The lower edge or margin of the valve member is inclined in different directions, at opposite sides of the ears, so that the valve member is adapted to occupy either of the two positions shown by Figures 15 and 16.

The valve member is provided with a port 33, opening on its convex face, and so arranged that when the valve member is in the position shown by Figure 15, the port is closed by the concave seat 21, and when the valve member is in the position shown by Figure 16, the port is in alignment with the bore 14, and the cap orifice 20, so that the valve is open.

The valve member and the cap head are 85 provided with interengaged coupling parts whereby, when the cap is partially rotated on the neck, the valve member is partially rotated on an axis at right angles with the axis of the cap, and thus moved to either its 90 closed or its open position. In this instance, the said coupling parts are an ear 34, projecting from the convex face of the valve member, and a recess 35 formed in the internal surface of the cap head and loosely receiving the stud, the recess being formed to impart a partial rotation to the valve member through the ear when the cap is turned. The ear may be formed on the cap and the recess in the valve member, if desired. The outer end of the neck may have a dome 13^a fitting the concave side of the valve member.

In assembling the parts the valve member is placed on the neck with its trunnion projections 31 in the bearings 32. The cap is 105 then applied to the neck to cause the recess 35 to receive the ear 34. The lower end of the cap is then crimped, to engage the neck groove 16. I prefer to provide a plurality of recesses 35, as shown by Figure 17, either recess being adapted to receive the ear, so that the cap may be held in either of several positions when placing it on the valve member and the neck, thus minimizing the difficulty of locating a recess in position to receive the ear.

The trunnion projections 31 may be adapted to bear yieldingly on the bearings 32, and thus exert outward pressure on the valve member, to press its convex face 120 against the concave seat 21. To this end the valve member may be cut, as indicated at 36 (Figure 11) to form tongues 37, on the free ends of which the trunnion projections 31 are formed, said tongues being biased, so 125 that their free ends normally spring downward.

As implied in the foregoing description and in the following claims, I am not limited to the specific devices of either of the em- 130

bodiments of the invention shown by the drawings except as otherwise required in certain of the more limited claims.

I claim:

- 5 1. A closure including three elements, viz, a tubular neck; a cap adapted to turn without endwise movement on the neck and provided with a central orifice and with a concave seat surrounding said orifice; and a 10 valve member interposed movably between said seat and the outer end of the neck, means being provided for permitting a partial rotation of the valve member on an axis at right angles with the axis of the cap, 15 the valve member being provided with a convex upper face bearing on said seat and with a port surrounded by said face; and coupling means adapted to impart a partial rotation from the cap to the valve member, the arrangement being such that when 20 the cap is turned in one direction, the valve port is located in alinement with the neck bore and cap orifice, and when the cap is turned in the opposite direction, the valve 25 port is covered by said seat.

2. A closure including three elements, viz, a tubular neck; a cap adapted to turn without endwise movement on the neck and provided with a central orifice and with a 30 concave seat surrounding said orifice; and a valve member interposed movably between said seat and the outer end of the neck, means being provided for permitting a partial rotation of the valve member on an axis 35 at right angles with the axis of the cap, said means being embodied in bearings on one of said elements, and trunnions on the said valve member movable in said bearings, the arrangement being such that when 40 the cap is turned in one direction, the valve port is located in alinement with the neck bore and cap orifice, and when the cap is turned in the opposite direction, the valve 45 port is covered by said seat.

3. A closure including three elements, viz, a tubular neck; a cap adapted to turn without endwise movement on the neck and provided with a central orifice and with a concave seat surrounding said orifice; and a 50 valve member interposed movably between said seat and the outer end of the neck, means being provided for permitting a partial rotation of the valve member on an axis 55 at right angles with the axis of the cap, the valve member being provided with a convex upper face bearing on said seat and with a port surrounded by said face; and coupling means adapted to impart a partial 60 rotation from the cap to the valve member, said coupling means being embodied in a recess in one of said elements, and an ear on the said valve member loosely entering said recess, the arrangement being such that when the cap is turned in one direction, the 65 valve port is located in alinement with the

neck bore and cap orifice, and when the cap is turned in the opposite direction, the valve port is covered by said seat.

4. A closure comprising a tubular neck; a cap fitting the neck, adapted to turn without endwise movement thereon, and provided with a central orifice spaced from the neck, a concave internal seat surrounding said orifice, and trunnion bearings at opposite sides of the orifice; a valve member interposed movably between the seat and the outer end of the neck, and provided with a convex upper face bearing on said seat, a port opening on said face, and oppositely projecting trunnions interposed between 70 said bearings and the outer end of the neck; and means operable by a turning movement of the cap to impart a compound movement to the valve member by turning it on a transverse axis in unison with the cap, and on a longitudinal axis independently of the cap, the arrangement being such that the cap may be turned in one direction to locate the valve port in alinement with the neck bore and with the cap orifice and in an 75 opposite direction to locate the valve port out of alinement with said bore and orifice, and in position to be closed by said seat.

5. A closure comprising a tubular neck; a cap fitting the neck, adapted to turn without endwise movement thereon, and provided with a central orifice spaced from the neck, a concave internal seat surrounding said orifice, and trunnion bearings at opposite sides of the orifice; a valve member interposed movably between the seat and the outer end of the neck, and provided with a convex upper face bearing on said seat, a port opening on said face, and oppositely projecting trunnions interposed between 80 said bearings and the outer end of the neck; and means operable by a turning movement of the cap to impart a compound movement to the valve member by turning it on a transverse axis in unison with the cap, and on a longitudinal axis independently of the cap, the arrangement being such that the cap may be turned in one direction to locate the valve port in alinement with the neck bore and with the cap orifice and in an 85 opposite direction to locate the valve port out of alinement with said bore and orifice, and in position to be closed by said seat.

5. A closure comprising a tubular neck; a cap fitting the neck, adapted to turn without endwise movement thereon, and provided with a central orifice spaced from the neck, a concave internal seat surrounding said orifice, and trunnion bearings at opposite sides of the orifice; a valve member interposed movably between the seat and the outer end of the neck, and provided with a convex upper face bearing on said seat, a port opening on said face, and oppositely projecting trunnions interposed between 90 said bearings and the outer end of the neck; and means operable by a turning movement of the cap to impart a compound movement to the valve member by turning it on a transverse axis in unison with the cap, and on a longitudinal axis independently of the cap, the arrangement being such that the cap may be turned in one direction to locate the valve port in alinement with the neck bore and with the cap orifice and in an 95 opposite direction to locate the valve port out of alinement with said bore and orifice, and in position to be closed by said seat.

6. A closure comprising a tubular neck having an annular concave seat surrounding its bore; a cap fitting the neck, adapted to turn without endwise movement thereon, and provided with an orifice spaced from the neck, a concave internal outer seat surrounding said orifice, and trunnion bearings at opposite sides of the orifice; a substantially spherical valve member having a 100

convex upper face fitting the cap seat, a convex lower face fitting the neck seat, a port opening on said faces, and oppositely projecting trunnions interposed between 5 said bearings and the outer end of the neck; and means operable by a turning movement of the cap to impart a compound movement to the valve member by turning it on a transverse axis in unison with the cap and on a 10 longitudinal axis independently of the cap, the arrangement being such that the cap may be turned in one direction to locate the valve port in alinement with the neck bore and with the cap orifice, and in an 15 opposite direction to locate the valve port out of alinement with said bore and orifice and in position to be closed by said outer seat.

7. A closure comprising a tubular neck; 20 a valve member bearing loosely on the outer end of the neck, and provided with a convex upper face and with a port opening on

said face, said valve member and neck being formed to permit a partial rotation of the valve member on an axis at right angles 25 with the axis of the neck; a cap adapted to turn on the neck and provided with a central orifice and with a concave seat surrounding said orifice; and coupling means adapted to impart a partial rotation to the 30 valve member when the cap is turned, the arrangement being such that when the cap is turned in one direction, the valve port is located in alinement with the neck bore and cap orifice, and when the cap is turned 35 in the opposite direction, the valve port is covered by said seat, the neck and cap being provided with interengaging means, whereby the cap is confined on the neck and is caused to confine the valve member on the 40 neck.

In testimony whereof I have affixed my signature.

ERNEST A. HUSSAR.
